United States Patent Office

Des. 198,154
Patented May 12, 1964

198,154

REFLECTIVE SIGN

Donald R. Hill, 501 N. 37th St., Belleville, Ill.

Filed May 27, 1963, Ser. No. 75,086

Term of patent 14 years

(Cl. D1—12)

FIG. 2

FIG. 3

FIG. 1

FIG. 5

FIG. 1 is a front perspective view of a reflective sign, embodying my new design.

FIG. 2 is an enlarged fragmentary front elevational view thereof, the rear being flat and plain;

FIG. 3 is a cross sectional view taken on line 3—3 of FIG. 2;

FIG. 4 is a cross-sectional view taken on line 4—4 of FIG. 2; and

FIG. 5 is an enlarged fragmentary front perspective view thereof.

Areas of the sign are shaded to indicate contrast.

I claim:

The ornamental design for a reflective sign, substantially as shown and described.
